CLAIM

The ornamental design for a massage element, as shown and described.

DESCRIPTION

FIG. 1 is a top perspective view of a massage element, showing our new design;

FIG. 2 is a top plan view thereof;

FIG. 3 is a bottom plan view thereof;

FIG. 4 is a front elevational view, the rear elevational, right and left side elevational views being mirror images thereof; and,

FIG. 5 is a bottom perspective view thereof.
